(57) **CLAIM**

The ornamental design for an ice pop maker, as shown and described.

DESCRIPTION

FIG. 1 is a top perspective view of an ice pop maker showing our new design.

FIG. 2 is a bottom perspective view thereof.

FIG. 3 is a top plan view thereof.

FIG. 4 is a bottom plan view thereof.

FIG. 5 is a right side view thereof, the left side view being identical.

FIG. 6 is a front view thereof, the rear view being identical.

FIG. 7 is an exploded top perspective view thereof showing associated molding cavities being inverted and an associated ice pop stick being removed therefrom.

FIG. 8 is a top perspective view thereof showing associated ice pop sticks inserted therein.

FIG. 9 is a top plan view of FIG. 8.

FIG. 10 is a right side view of FIG. 8, the left side view being identical; and,

FIG. 11 is a front view of FIG. 8, the rear view being identical. The ice pop maker in FIGS. 1-6 is shown without the sticks for ease of illustration.
